UNITED STATES PATENT OFFICE.

JUDSON J. HILTON, OF MURRAYSVILLE, WEST VIRGINIA, ASSIGNOR TO
GEORGE H. FERNALD, OF NORTH EAST, PENNSYLVANIA.

COMBINED WHISK-BROOM BRACKET AND COAT-HOOK.

SPECIFICATION forming part of Letters Patent No. 533,847, dated February 5, 1895.

Application filed March 23, 1894. Serial No. 504,768. (No model.)

To all whom it may concern:

Be it known that I, JUDSON J. HILTON, of Murraysville, in the county of Jackson, in the State of West Virginia, have invented new and useful Improvements in a Combined Whisk-Broom Bracket and Coat-Hook, of which the following, taken in connection with the accompanying drawing, is a full, clear, and exact description.

10 This invention relates to combined whisk-broom racks, or brackets, and coat hooks, as a new article of manufacture.

My object is to produce, as a new article of manufacture, a broom bracket and a coat hook, all constructed from a single piece of wire, cheap and durable in its construction and of great utility; and to that end my invention consists in the several new and novel features hereinafter described and which are 20 specifically set forth in the claim hereunto annexed.

It is constructed as follows, reference being had to the accompanying drawing, in which I have represented a front elevation of my improvements.

I first take a piece of wire —*a*— and bend it centrally to form a loop —*b*—, said loop being bent upwardly to form a hook —*c*—. The body or adjacent parts of the wire are then 30 bent laterally or twisted around each other, as shown at —*d*— to form a stiff shank to support

the hook. The parts are then bent so as to diverge at the point —*e*— and again bent at —*f*— downwardly forming a loop or eye —*g*— and are thence bent to form the lateral hooks 35 or arms —*h*— which serve to hold the broom. The ends of the wire are then passed through the eye —*g*— so as to form a support for the downwardly and converging arms —*i*—, and the ends of the wire are then bent or twisted 40 together so as to form an eye —*k*— by which the device is hung or otherwise supported.

What I claim is—

The herein described bracket and hook constructed from a single piece of wire by first 45 bending it substantially centrally to form a loop, then bending the loop upwardly to form a hook, thence twisting wires laterally upon each other to form a shank, thence diverging them, thence bending them to form an eye 50 —*g*—, thence bending them to form the lateral arms —*h*—, passing the ends of the wire through the eye —*g*— for the purpose of supporting the hook and shank, thence twisting the ends together to form eyes for the purpose 55 of supporting the same.

In witness whereof I have hereunto set my hand this 20th day of February, 1894.

JUDSON J. HILTON.

In presence of—

GUY WALLACE,
I. M. WALLACE.
